[57] ABSTRACT

A silicon carbide, three-phase heating element having a hollow, generally cylindrical body formed with three circumferentially spaced legs comprising the cold end section and three spaced, parallel spirals constituting the hot zone section and terminating in a common juncture. The slots between the spirals can be filled with a ceramic insulating material.

THREE-PHASE HEATING ELEMENT

BACKGROUND OF THE INVENTION

This invention relates generally to heating elements and, more particularly, to electrical heating elements of the three-phase electrical resistance type formed of silicon carbide.

The known three-phase silicon carbide elements available today consist of three elongated parallel, silicon carbide rods, each having a low resistance portion and a high resistance portion. The high resistance portions are connected to a common bridging member having cylindrical plugs received in the open ends of the hollow rods and rigidly secured thereto by weldments. Such known heating elements are especially adapted for use in the production of float glass wherein a large number of these elements, on the order of from 600 to 1,500 elements for example, are vertically suspended from the roof of a large furnace above the level of the molten material on which the flat glass product floats. In mounting each of these known elements, the three rods are fitted in the bores of a frustoconical refractory block disposed in a correspondingly shaped hole in the top wall of the furnace.

Such known silicon carbide heating elements have not been entirely satisfactory because of the weakness inherent at the weldments between the rods and the bridging member and which are subjected to stresses induced therein during the heating thereof. The stresses generated at the weldments cause premature failure of the heating element. Also, the peculiar and awkward shape of these known fragile elements renders them susceptible to breakage during handling and shipping. Furthermore, in replacing one or more spent elements, the specially configurated refractory blocks must be removed or the elements inserted from within the furnace, which is not feasible while the furnace is in operation. The tendency for the refractory blocks to adhere to the furnace walls also compounds the problems encountered in element removal and replacement.

SUMMARY OF THE INVENTION

A primary object of the present invention is to provide an improved three-phase, silicon carbide heating element avoiding the above noted disadvantages and which is formed in a unitary, one-piece construction.

Another object of this invention is to provide an improved silicon carbide heating element of the three-phase electrical resistance type which is strong and rigid in construction, rugged and durable in use, compactly and homogeneously formed, and which is readily installed and replaced during furnace operation at a minimum of inconvenience.

The heating element of the present invention is characterized by the provision of a unitary, one-piece cylindrical body formed of silicon carbide having three elongated, laterally spaced legs forming the cold end terminal section and three parallel spirals constituting the hot zone section of the element. The spirals extend from the inner ends of the legs in a helical path along the body and terminate in a common end junction. An insulating filler material can be deposited in the slots separating the spirals.

The foregoing and other objects, advantages, and characterizing features of the present invention will become clearly apparent from the ensuing detailed de-

scription of an illustrative embodiment thereof, taken together with the accompanying drawing wherein like reference numerals denote like parts throughout the various views.

BRIEF DESCRIPTION OF THE DRAWING FIGURES

FIG. 1 is a side elevational view of a three-phase heating element constructed in accordance with this invention;

FIG. 2 is an elevational view of one end thereof, as viewed from the left toward the right in FIG. 1;

FIG. 3 is a cross sectional view, taken about on line 3-3 of FIG. 1;

FIG. 4 is an elevational view of the end opposite that shown in FIG. 2;

FIG. 5 is a view similar to FIG. 1, showing an insulating filler material deposited in the spiral slots between adjacent convolutions of the spirally configurated hot zone section; and

FIG. 6 is a cross sectional view, taken about on line 6-6 of FIG. 5.

DETAILED DESCRIPTION OF AN ILLUSTRATIVE EMBODIMENT

Referring now in detail to the illustrative embodiment depicted in the drawings, and in particular to FIG. 1, there is shown a heating element, generally designated 10, constructed in accordance with this invention, comprising an elongated, hollow, tubular cylindrical outline and provided with a bore 14 (FIG. 2) extending axially therethrough.

Resistance body 12 is formed in a unitary, one-piece construction of a homogeneous mass of very dense, self-bonded or recrystallized silicon carbide material capable of withstanding elevated operating temperatures without disintegration or material deterioration, is non-corrosive, and which changes in resistance very slightly, slowly and uniformly in use to provide stable heating over a long period of use.

Resistance body 12 includes a cold zone terminal section 16 and a hot zone section 18. In forming the cold zone terminal section 16 in the solid cylindrically shaped wall of resistance body 12, three elongated, equally circumferentially spaced slots 20, 22 and 24 are cut through the radial wall thickness of body 12 extending axially inwardly from one end 26 thereof to form three arcuately shaped, circumferentially spaced elongated members or legs 28, 30 and 32.

The hot zone section 18 is similarly formed by cutting three parallel, spiral slots 34, 36 and 38 through the radial wall thickness of resistance body 12, forming continuations of slots 20, 22 and 24 and extending from the inner ends thereof toward the opposite end 40 of resistance body 12 to form three parallel spirals 42, 44 and 46. These spirals 42, 44 and 46 are connected at their inner ends to legs 28, 30 and 32 and are formed integral therewith. Spirals 42-46 extend in a helical path longitudinally of the remaining portion of resistance body 12 and terminate in a common terminal end juncture or "Wye" connection 48 adjacent the opposite end 40 of resistance body 12.

The resistance of spirals 42, 44 and 46 is significantly greater than the resistance of their associated legs 28, 30 and 32 because of the appreciably smaller cross sectional areas of the former relative to the latter. Thus, when power is supplied to heating element 10, the

higher resistance of spirals 42-46 generates high temperatures therein to form the hot zone or effective heating portion of element 10.

The higher resistance offered by the reduced cross sectional areas of the spirals 42, 44 and 46 enables resistance body 12 to be formed of a very dense silicon carbide material without sacrificing resistance capabilities as opposed to the less dense silicon carbide materials incorporated in the solid walls of the hollow resistance rods employed in the known heating elements used today. Since an increase in material density generally decreases the resistance of a body, the density of these known elements must necessarily be seriously compromised in obtaining desired resistance capabilities. By controlling the cross sectional areas of spirals 42-46 to determine resistance capabilities and because resistance body 12 is of a unitary, homogeneous construction throughout, the density thereof can be appreciably increased as opposed to known silicon carbide heating elements, which densities are dictated by resistance design requirements. By way of example, the density of resistance body 12 of this invention can vary from about 2.7 to 2.8 grams/cc as contrasted to known silicon carbide heating elements which have densities ranging from about 2.2 to 2.4 grams/cc. The increased density of the silicon carbide material forming the heating element 10 of the present invention adds greater stability and strength thereto.

For additional strength, the spaces defined by spiral slots 34, 36 and 38 between adjacent windings or convolutions of spirals 42, 44 and 46 can be filled with an impervious, insulating filler material 50, as shown in FIGS. 5 and 6. This added strength offers flexibility in design, enabling the hot zone portion to be extended and the cross sectional areas of the spirals 42-46 reduced to increase resistance, as desired, since the filler material 50 forms with the spirals 42-46 a continuous cylindrical wall. Moreover, the insulating filler material 50 closes slots 34-38 to preclude the accumulation of undesirable contaminants therein, which could promote short circuiting or induce stresses in the hot zone section 18 to cause premature failure of heating element 10.

Insulating material 50 is comprised of a zircon base, ceramic insulating material provided with a suitable binder and has a coefficient of thermal expansion substantially similar to that of silicon carbide to avoid stresses in heating element 10 caused by thermal variations. Moreover, such material, which is described and claimed in copending application, Ser. No. 398,185, filed simultaneously herewith, is capable of withstanding the operating temperatures of heating element 10 without decomposing or becoming electrically conductive and remains stable in both reducing and oxidizing atmospheres over the entire temperature operating range of heating element 10.

A coating of any suitable electrical conducting material 52, such as aluminum for example, can be sprayed or otherwise deposited on the outer and inner surfaces of legs 28, 30 and 32 adjacent end 26 to provide electrical terminals for resistance body 12. Various electrical contact arrangements, provided with conductors leading to a suitable source of electrical power, can be connected to the terminals provided by the electrical conducting material 52. Also, if desired, insulating spacers can be placed between the opposed surfaces of adjacent legs 28, 30 and 32 to maintain them in a properly

spaced relation and preclude short circuiting therebetween.

From the foregoing, it is apparent that the present invention accomplishes its intended objects. The provision of a three-phase electrical heating element formed of a unitary, one-piece construction of a dense, recrystallized silicon carbide avoids stresses otherwise generated in welded multiple rod elements of known construction. The elimination of such stresses in the heating element of this invention minimizes fractures and breakage to prolong the useful, operating life thereof. Also, because the heating element is formed in a compact, rod like configuration, it can be easily handled to decrease the possibilities of damage during handling and shipping. Moreover, the heating element of this invention requires only a minimum of supporting structure and can be simply inserted through a suitable bore in a furnace wall for ease of installation and replacement. The provision of electrical termination at one end only simplifies the attachment of electrical connections thereto, further facilitating installation and replacement. Indeed, the heating element of this invention can be efficiently replaced while the furnace is operating, thereby eliminating furnace shutdown time. By filling the spiral slots in the heating section with the desired insulating material, a stronger heating element is provided and contaminant accumulation is appreciably reduced.

A preferred embodiment of this invention having been described and illustrated in detail, it should be understood that this has been done by way of illustration only.

I claim:

1. A heating element comprising: an elongated hollow body formed of a dense, non-metallic, electrical resistance material; said body having a cold zone section and a hot zone section; said cold zone section comprising three laterally spaced elongated members extending longitudinally inwardly from one end of said body; each of said elongated members being provided with electrical conducting material to provide electrical terminals for said hollow body; said hot zone section comprising three spaced, parallel spirals connected to the inner ends of said elongated members, respectively, and extending therefrom in a helical path longitudinally along substantially the remainder of said body; said spirals terminating in a common end juncture; each of said spirals having a lesser cross sectional area than the elongated member to which it is joined; said spirals being spaced from each other by spiral slots formed in said body; and a zircon base ceramic insulating filler material permanently disposed in said slots between said spirals preventing accumulation of contaminants and for strengthening said element, said filler material having a coefficient of expansion substantially similar to the coefficient of expansion of said electrical resistance material, said filler material remaining in said slots and being capable of withstanding temperatures over the entire operating temperature range of said heating element from room temperature up to about 3,100°F.

2. A heating element according to claim 1 wherein said body is formed in a unitary one-piece construction of a homogeneous mass of said non-metallic, electrical resistance material.

3. A heating element according to claim 1 wherein said electrical resistance material is dense, recrystallized silicon carbide.

4. A heating element according to claim 2 wherein said electrical resistance material is dense, recrystallized silicon carbide.

5. A heating element according to claim 1 including a coating of said electrical conducting material deposited on the outer surfaces of said elongated members adjacent said one end of said body.

6. A heating element according to claim 1 wherein said electrical resistance material is dense, recrystallized silicon carbide and said body is formed in a unitary one-piece construction of a homogeneous mass of said dense, recrystallized silicon carbide; and a coating of said electrical conducting material deposited on the outer surfaces of said elongated members adjacent said one end of said body.
